UNITED STATES PATENT OFFICE.

MOSES B. DISKIN, OF NEW YORK, N. Y.

PRINTING-PRESS.

1,186,295.

Specification of Letters Patent.

Patented June 6, 1916.

Application filed June 17, 1915. Serial No. 34,632.

To all whom it may concern:

Be it known that I, MOSES B. DISKIN, a citizen of the United States, and a resident of the city of New York, borough of Manhattan, in the county and State of New York, have invented a new and Improved Printing-Press, of which the following is a full, clear, and exact description.

My invention relates to printing presses, and has reference more particularly to a hand press mainly intended for printing in two different colors.

An object of the invention is to provide a simple, inexpensive, and efficient hand press for printing labels in which the numbers or letters indicating the measure or price are printed in a different color from the reading matter relating thereto.

A further object of the invention is to provide a hand press having a detachable chase which can receive ordinary type or a special plate.

With the above and other objects in view, the nature of which will more fully appear as the description proceeds, the invention consists in the novel construction, combination and arrangement of parts as herein full described, illustrated and claimed.

In the accompanying drawings, forming part of the application, similar characters of reference indicate corresponding parts in all the views.

Figure 1 is a side elevation of an embodiment of my invention, a part of which is broken out to show the details of construction; Fig. 2 is an end elevation on line 2—2, Fig. 1; Fig. 3 is a side elevation of the slide or chase carrier; Fig. 4 is an end elevation of an inking roller and the arm carrying it; Fig. 5 is a side elevation of the arm with a fragment of the roller; Fig. 6 is a longitudinal section of the inking roller; and Fig. 7 is a plan view of the chase.

Referring to the drawings, 8 represents the frame standards which are united by a bed or table 9, preferably forming an integral part of the standards and disposed substantially horizontally. Each of the standards has a substantially vertical slot 10 above the table engaged by a cross-head 11 provided on each side of the chase holder or slide 12. An adjustable connecting rod 13 binds each of the cross-heads to a corresponding eccentric 14 which are, in turn, keyed to a driving shaft 15 bearing in the frame standards below the bed 9. A driv-

ing pulley 16 is provided on the shaft when the same is to be actuated by power; otherwise a crank can be connected to the shaft.

The chase holder 12 has an under-cut 60 groove 17 at the bottom thereof into which the bottom of the chase 18 fits snugly. The chase 18 has an under-cut recess 19 adjacent each end, and in each recess there is a groove 20 for the type 21. The type is retained 65 within the chase by screws 22 provided at each end of the grooves within the chase. The recesses 19, when there is no type in the grooves, are adapted to receive a plate 23, as indicated in Fig. 7, which plate has the 70 ends thereof properly beveled to fit into the under-cut recess 19 and which is retained in the recess by means of screws 24 provided at each side of the recess. This plate, as indicated, has the outline of a label on which 75 certain type is formed. In this particular case, the plate has the words "Price" and "Lot", with lines relating thereto. The type shown in Fig. 7 is intended to carry numbers which will print on the lines in a different 80 color. It is self-evident that the number of grooves 20 in the chase may be varied in accordance with the plate used.

Coöoperating with the chase in the chase holder is an inking device for each end of the 85 chase. A self-feeding ink roller 25 of the inking device comprises a perforated tubular member 26, at one end of which a flange 27 is provided to form an abutment for a sleeve 28 of textile material surrounding the 90 tube and which becomes saturated by the ink which passes from the tube through the perforations thereof. The other end of the tube 26 has a flange plug 29 which closes the tube 26 and locks the sleeve 28 thereon. The 95 flanged end of the tube and the plug have trunnions 30 each of which bears in a head 31 the stem 32 of which projects into an arm 33, which arms are rigidly secured to a shaft 34 bearing in the standards 8. The head 31 is forced toward the arm 33 by a spring 35 mounted on the stem 32, consequently the tendency of the springs is to move the inking roller toward the chase located within the chase-holder.

It will be noted that each of the inking devices has a crank 36 which is connected by a link 37 to the top of the chase-holder 12, so that a displacement of the chase-holder by the eccentric 14 will cause a displacement 110 of the inking devices on their shafts 34. To prevent the inking rollers from supplying

too much ink to the plate and type in the chase under the pressure of the springs 35, a guide roller 38 is provided on each head 31 which, under the action of the spring, engages the bottom of the chase-holder 12, and this engagement prevents an excessive pressure. The ends of the chase-holder 8 are rounded so as to provide clearance for the inking rollers when the inking rollers are clearing the chase while the holder moves downward under the action of the eccentric.

Mounted between the standards adjacent one end of the table is a paper-feed, the roller 39 of which has a ratchet 40 engaged by a spring-pawl 41 mounted on an arm 42 which is co-axial with the ratchet and free to oscillate relative thereto. An adjustable connecting-rod 43 binds the arm to a crank 44 forming part of the eccentric 14, the crank pin 43' being adjustable by a screw 44'. The displacement of the crank 44 causes an oscillation of the arm, which arm will move the ratchet when it oscillates in the direction of the arrow shown in Fig. 1, and therewith the roller 39. The return oscillation of the arm will not disturb the ratchet; thus the feed is only in one direction. The roll of paper 45 on which the subject matter is to be printed is mounted in brackets 46 extending from the standards 8. A guide roll 47 is also mounted in brackets 48 extending from the standards above the brackets 46 and adjacent the roller 39. The guide roller 47 has adjustable sleeves 49 which can be shifted thereon to engage the edges of the paper and prevent any lateral movement thereof on the roller 47 and, therefore, on the roller 39.

The paper from the roll passing over the roller 39 is pressed thereagainst by a roller 50 rotatably mounted in a block 51 which is adjustable within a bridging member 52 by means of a screw 53 mounted in the bridging member, and whereby the pressure of the roller 50 on the roller 39 can be varied. One end of the bridging member is pivotally connected to one of the standards 8, while the other end can be secured to the other standard by a screw. This arrangement permits the swinging of the bridging member 52 to one side when threading the paper, or for any other purposes, as the case may be.

It will be noted that the feed of the paper is controlled by the crank 44, and, therefore, the feed of paper is interrupted when the chase-holder 12 approaches the paper on the bed, so that there is no feed during the contact of the type with the paper on the bed.

Positioned on the other end of the table is a perforating or cutting device 54, which comprises a stationary member above the table bridging the two standards 8 and in which a punching member 55 is mounted, and which is normally maintained clear from the table by a spring 56. The same is

brought against the table by a member 57 secured to the chase-holder 12 and adapted to move therewith. It will be noted that the member 57 will engage the punching member 55 when the chase-holder approaches the table and when the feed of paper is interrupted.

The operation of the device is as follows: The two inking rollers 25 are preferably filled with ink of different colors, so that the type 21 is inked with one color and the plate 23 is inked with a different color. It will be seen that when the eccentric moves the chase-holder 12 downwardly, the inking rollers will apply ink thereto and clear the chase-holder as the same approaches the paper. After contacting with the paper, the chase-holder returns to its normal or upper position, causing the arms carrying the rollers to swing to their position, shown in dotted line in Fig. 1, consequently applying ink to the type and plate in the chase. Therefore, it will be noted that ink is applied twice by the inking device, and, thus, is more uniformly distributed to the type and plate carried by the chase.

By providing the adjustable connecting rod 43 and crank pin therefor, the length fed can be varied, and therefore the size of paper fed from the roller 15 intermittently can be varied. The reason for that is to permit the printing of labels of different lengths in accordance with the purpose for which they are designed. The connecting rod 18, which is also adjustable, permits the utilization of the printing press with paper of different thicknesses; that is, it can be as efficiently used on pasteboard as on thin paper. It may be further remarked that in my press the inking device simultaneously applies different colors to the printing surface of the press; that is to say, to the plate and type carried by the chase.

While I have described the principle of operation, together with the press which I now consider to be the best embodiment thereof, I desire to have it understood that the press shown is merely illustrative, and that such changes may be made as are within the scope of the appended claims.

I claim:

1. In a printing press of the class described, a work bed, a chase-holder mounted to reciprocate to and from the bed, a chase associated with the holder, an inking roller for each of the ends of the chase normally located adjacent the central part of the chase, swinging arms carrying each of the inking rollers, a resilient member normally moving the roller toward the chase, a roller carried by the arms and in engagement with the holder whereby an excessive pressure by the rollers on the chase is prevented; means connecting the arms to the holder whereby the same are caused to swing when the

- holder is reciprocated, means for reciprocating the holder, means for feeding paper on the bed operable by the means for reciprocating the holder, and punching means associated with the bed and operable by the displacement of the holder, substantially as and for the purpose set forth.
2. In a printing press of the class described, a work-bed, a chase-holder mounted to reciprocate to and from the bed, means for reciprocating the holder, a connecting rod the length of which may be varied, binding the holder to the means for reciprocating the same, a chase associated with the holder, an oscillating inking device for applying two different colors to the printing matter in the chase, means connecting the inking device to the holder whereby the same is oscillated when the holder is reciprocated, an intermittent paper feed for advancing the paper over the bed, a rod the length of which may be varied, connecting the feed to the means for reciprocating the holder whereby the feed is operated.
3. In a printing press of the class described, including a chase-holder and means for reciprocating the chase-holder, a paper roll, a pawl and ratchet mechanism for advancing the paper from the roll to the chase-holder, a rod the length of which may be varied, connecting the pawl and ratchet mechanism to the means for operating the holder, and adjustable means intermediate the rod and the holder-operating means whereby the length of paper fed by the pawl and ratchet

mechanism may be varied, as and for the purpose set forth.

4. In a printing press of the class described, a work-bed, a chase-holder mounted to reciprocate to and from the bed, a chase associated with the holder, an inking roller for each of the ends of the chase, normally located adjacent the central part of the chase, swinging arms carrying each of the inking rollers, a resilient member normally moving the roller toward the chase, a roller carried by the arms and in engagement with the holder whereby excessive pressure by the rollers on the chase is prevented, means connecting the arms to the holder whereby the same are caused to swing when the holder is reciprocated, means for reciprocating the holder, a rod the length of which may be varied, connecting the means for reciprocating the holder with the holder, whereby paper of various thicknesses may be printed, means for feeding paper intermittently, operable by the means for reciprocating the holder, means for varying the length of paper fed, and means associated with the bed and operable by the displacement of the holder, for punching the lengths fed by the feed mechanism.

In testimony whereof I have signed my name to this specification in the presence of two subscribing witnesses.
